JOHN MOORE SAMUEL, OF DOUGLAS, ARIZONA

CONTAINER FOR HOT COMMINUTED MATERIAL

Application filed November 7, 1931. Serial No. 573,710.

This invention relates to a bin or container for particles of hot solid material which may be introduced into the bin or container and kept hot for some time and can be withdrawn while still hot. The invention is especially useful in connection with the storing of hot calcined ore after it is taken from the calciners and before it is introduced into the smelters, but the invention is not restricted to this particular use.

Heretofore, attempts to provide bins or containers which prevent loss of heat from hot material therein have resulted in very expensive installations, as linings of heat insulating materials are costly and maintenance of the same is often troublesome. For example, when brick linings are used for bins for hot calcined ore the ore often sticks to the brick lining and when dislodged by hammering the bin sides or poking through holes in the roof the lining is often damaged. If heat resisting alloys are used on the inner shell to protect the lining of heat insulating material the cost is even greater.

By the present invention bins or containers are made having relatively thin and inexpensive metal walls and provision is made so that some of the particles of the hot solid material that are introduced into the bin are caused to form a stationary lining along the inside walls. The stationary lining composed of the particles of material which are introduced prevent escape of heat from the other portion of the material, as this lining forms a heat insulating layer adjacent the inner walls of the container.

The invention will be understood from the description in connection with the accompanying drawings in which Fig. 1 is a longitudinal section through an illustrative embodiment of the invention taken along the line 1—1 of Fig. 2; Fig. 2 is a vertical section taken along the line 2—2 of Fig. 1; Fig. 3 is a side view partly broken away showing a modification of some of the elements; Fig. 4 is a section at right angles to Fig. 3 and Fig. 5 is a vertical section partly broken away corresponding to Fig. 2 showing a modification.

In the drawings reference character 1 indi-

cates a bin or receptacle that may be provided with an arch-shaped top or cover 2 that may be made of refractory material which is a good heat insulator. The side walls 3 of the bin are indicated as sloping inwardly and the bin is provided with a curved bottom 4 and also vertical ends 5.

One or more openings 6 may be provided through the cover 2 for introduction of hot material and one or more similar openings 60 may be provided in the bottom for withdrawing the hot material.

I-beams 7 are installed along opposite sides of the bin or container for supporting the same. Channel bars 8 may be connected 65 along the outsides of the I-beams 7 for strengthening purposes. Angle bars 9 are connected along the insides of the beams 7 for supporting the roof or cover 2, the edges of which bear against inside surfaces of the 70 webs of the I-beams 7. Rivets 10 passing through the webs of the I-beams 7, flanges of the channels 8, flanges of the angle bars 9, and the upper edges of the side walls 3 hold these members securely together.

Channel bars 11 extend across the ends of the bin on the outside and angle bars 12 are connected to the channels 11 along the inner sides thereof by means of rivets 13 which pass through the channel bars 11, 80 flanges of the angle bars 12, and the upper edges of the end walls 5 of the bin. These members are thus kept securely fastened together. Walls 14 of refractory blocks, such as brick or tile, are supported on the angle 85 bars 12 at the ends of the roof or cover 2 to close the spaces.

A series of spaced shelves 15 which may be in the form of troughs made up of plates with 90 sides at right angles to each other are installed along the inside of the ends 5 of the bin with the plates at 45° to the horizontal. Metal straps 16 are provided for keeping the shelves 15 in place near the walls 5 in position to catch and retain particles of material that are introduced into the bin. The outer ends of the straps 16 are bent downwardly and connected to the shelves as indicated at 17. The intermediate portions of the straps 16 95 are connected to the shelves 15, as shown at 100

18, and the upper ends of the straps 16 are bent downwardly as indicated at 19, and lie in spaces between the inner surfaces of the walls 5 and bent-out portions of cleats 20 5 that are riveted to the walls 5 by means of the rivets 21.

A series of spaced shelves 22 similar to the shelves 15 are placed along the inner sides of the side walls 3 of the bin. Straps 23 similar to the straps 16 keep the shelves 22 in place. The lower ends of the straps 23 are bent downwardly and connected to the shelves as indicated at 24. The intermediate portions of the straps 23 are connected to the shelves 22, as indicated at 25 and the upper ends of the straps 23 are bent downwardly, as indicated at 26 and extend into spaces between the inner sides of the walls 3 and bent-out portions of the cleats 27 which are riveted to the walls 3, as indicated at 28.

In the modification shown in Figs. 3 and 4 the shelves 15 are kept in place by being suspended from above with spaces between them, instead of being held in place by means 25 of straps riveted to the walls 5. In this modification bolts 30 having heads 31 at the bottom extend through holes provided therefor in the angle bars 12 and are kept in place and adjusted in position by means of nuts 32 on 30 the bolts 30. Spacers 33 which are threaded upon the bolts 30 keep the shelves 15 spaced the desired distances apart. The spacers 33 are provided with heads 34 at their upper ends having V-shaped grooves therein to fit 35 the outside of the shelves 15 and also with V-shaped heads 35 at their lower ends to fit the inside of these shelves 15. The spacer below the lowest shelf 15 and the spacer above the highest shelf 15 are similar to corresponding parts of the other spacers. U-bolts 36 pass around spacers 33 near the lower ends 40 of the bolts 30 and are kept in place in the walls 5 by means of nuts 37 to prevent the suspended members from swinging.

In the modification shown in Fig. 5 the shelves 22 are kept in place by means of bolts 30 instead of straps. Spaced bolts 38 may extend from the upper flange of the I-beam 45 through the angle bars 9 to help support these angle bars, the bolts 38 being adjusted in position for this purpose by means of the nuts 39. Lugs 40 rest upon the angle bars 9. Holes are provided through the lugs 40 and angle bars 9 through which the bolts 30 pass, and are adjusted in position for sustaining the troughs 22 by means of the nuts 32.

When the bin is used for retaining calcined ore preparatory to introducing it into a reverberatory furnace the hot calcined particles 60 are introduced at the top and are withdrawn from the bottom into the reverberatory furnace without appreciable loss of heat. In view of the fact that the temperature must be very high in the reverberatory furnace for 65 smelting the ore, whatever heat is retained

in the calcined ore as it is introduced is thereby saved, thus effecting a decided economy in the process. The particles which are caught by the shelves form a heat insulating lining for the bin whether calcined ore or other material is stored in the bin, so that the material can be kept in the bin for a considerable length of time and then removed while still retaining its heat.

The above described embodiments of the invention are the preferred ones for retaining a layer of particles of segregated material on the walls of a bin to act as a heat insulator for the retention of the heat of the hot material, stored in the bin. It is obvious that when a 75 layer of the material is retained against the walls, the material so retained in that layer will gradually cool down; therefore any structure designed to achieve this end, must be free to expand and contract without causing deformation of the main bin structure. 85

Were it not for the temperature stresses due to unequal expansion, it would be possible to effect the purpose of the invention by building the bin with two shells, an inner shell and an outer shell, the distance between them being equal to the thickness of the material needed to furnish the required heat insulation, and filling the space between the inner and outer shells with particles of the 90 segregated material. While this would be the simplest possible construction, the result would be that the inner shell would attain a temperature only slightly less than that of the material stored in the bin while the temperature of the outer shell would be only somewhat higher than the atmospheric temperature. The inner shell would therefore expand much more than the outer shell. If the double shelled bin were built so as to 100 permit or provide for this unequal expansion, fine material could not be stored in it without excessive leakage occurring; on the other hand if the double walled bin were built so as to be tight to fine material, the 110 unequal expansion of the two shells would cause excessive deformation of the bin and ultimate failure.

It is to be understood that my invention is not limited to the embodiment shown herewith, they being merely the preferred means of embodying the invention but that any structure that comes within the scope of the claims and retains a layer of the material 115 against the walls without at the same time introducing undue temperature stresses in the structure is within this invention.

I claim:

1. In a container for particles of hot solid material, means along walls of said container 125 to catch particles of said material as they pass downwardly and maintain them in proximity to said walls, said means comprising shelves parallel to said walls.

2. In a container for particles of hot solid 130

material, means along walls of said container to catch particles of said material as they pass downwardly and maintain them in proximity to said walls, said means comprising shelves spaced one above another along said walls.

3. In a container for particles of hot solid material, means along walls of said container to catch particles of said material as they pass downwardly and maintain them in proximity to said walls, said means comprising shelves parallel to said walls, and having particle-retaining surfaces sloping in two directions.

15 4. In a container for particles of hot solid material, means along walls of said container to catch particles of said material as they pass downwardly and maintain them in proximity to said walls, said means comprising shelves parallel to said walls, and having particle-retaining surfaces sloping in two directions, one of which is toward a wall and another away from it.

25 5. In a container for particles of hot solid material, means along walls of said container to catch particles of said material as they pass downwardly and maintain them in proximity to said walls, said means comprising shelves parallel to said walls, and straps

30 for keeping said shelves in place.

6. In a container for particles of hot solid material, downwardly extending walls, and means along said walls to catch particles of said material as they pass downwardly and maintain them in proximity to said walls, said means comprising surfaces in proximity to said walls upon which particles of said material rest.

7. In a container for particles of hot solid material, downwardly extending walls, and means along said walls to catch relatively thin layers of particles of said material as they pass downwardly and maintain them in proximity to said walls, said means comprising surfaces in proximity to said walls upon which particles of said material rest.

8. In a bin for storing particles of hot solid material, means to cause a portion of said material to be retained along said walls and retard escape of heat from the remainder of the material, said means comprising shelves parallel to said walls and spaced one above another along said walls.

9. In a bin for storing particles of hot solid material, means to cause a portion of said material to be kept in fixed positions along walls of said bin and retard escape of heat from the remainder of the material, said means comprising shelves parallel to said walls and having particle retaining surfaces sloping in two directions, one of which is toward a wall and the other away from it.

JOHN MOORE SAMUEL.
